(57) **CLAIM**

The ornamental design for a pet dental chew, as shown and described.

DESCRIPTION

FIG. 1 is a perspective view of a pet dental chew showing a new design;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken lines in the drawings show portion of the pet dental chew that form no part of the claimed design.

The broken lines illustrate a break in length in the pet dental chew that forms no part of the claimed design. The surface between the break does not form part of the claimed design. Additionally, all other broken lines in the drawings show portions of the pet dental chew that form no part of the claimed design.
